[57] CLAIM

The ornamental design for a cup shaped sole, as shown and described.

DESCRIPTION

FIG. 1 is a bottom plan view of a cup shaped sole showing a first embodiment of my new design;

FIG. 2 is a cross sectional view of the cup shaped sole taken along line 2—2 of FIG. 1;

FIG. 3 is a cross sectional view of the cup shaped sole taken along line 3—3 of FIG. 1;

FIG. 4 is a cross sectional view of the cup shaped sole taken along line 4—4 of FIG. 1;

FIG. 5 is a cross sectional view of the cup shaped sole taken along line 5—5 of FIG. 1;

FIG. 6 is a side elevational view of one side of the cup shaped sole of FIG. 1;

FIG. 7 is a cross sectional view of the cup shaped sole taken along line 7—7 of FIG. 6;

FIG. 8 is a cross sectional view of the cup shaped sole taken along line 8—8 of FIG. 6;

FIG. 9 is a side elevational view of the other side of the cup shaped sole of FIG. 1;

FIG. 10 is a front elevational view of the cup shaped sole of FIG. 1;

FIG. 11 is a rear elevational view of the cup shaped sole of FIG. 1;

FIG. 12 is a bottom plan view of a cup shaped sole showing a second embodiment of my new design;

FIG. 13 is a cross sectional view of the cup shaped sole taken along line 13—13 of FIG. 12;

FIG. 14 is a cross sectional view of the cup shaped sole taken along line 14—14 of FIG. 12;

FIG. 15 is a cross sectional view of the cup shaped sole taken along line 15—15 of FIG. 12;

FIG. 16 is a cross sectional view of the cup shaped sole taken along line 16—16 of FIG. 12;

FIG. 17 is a cross sectional view of the cup shaped sole taken along line 17—17 of FIG. 12;

FIG. 18 is a side elevational view of one side of the cup shaped sole of FIG. 12;

FIG. 19 is a side elevational view of the other side of the cup shaped sole of FIG. 12;

FIG. 20 is a front elevational view of the cup shaped sole of FIG. 12; and
FIG. 21 is a rear elevational view of the cup shaped sole of FIG. 12.
The broken line showing of a shoe upper and the inter-

nal top and side surfaces of the sole cross sections are
for illustrative purposes and form no part of the claimed
design.
